UNITED STATES PATENT OFFICE.

JOHN LUND, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

ELEVATING AND SIGHTING MECHANISM FOR GUNS.

1,298,982.

Specification of Letters Patent.

Patented Apr. 1, 1919.

Application filed April 8, 1916. Serial No. 89,902.

To all whom it may concern:

Be it known that I, JOHN LUND, a citizen of the United States, and resident of Bethlehem, Northampton county, State of Pennsylvania, have invented certain new and useful Improvements in Elevating and Sighting Mechanism for Guns, of which the following is a specification.

This invention relates to elevating and 10 sighting mechanism for guns and it is particularly adapted for field guns, although useful with guns of other types. The invention will be described in connection with the accompanying drawing, in which:

15 Figure 1 is a side elevation of a field gun embodying the invention, portions of the gun barrel and trail being broken away and the wheels being indicated by broken lines; and

20 Fig. 2 is a view of the opposite side of the gun, parts being broken away and part being shown in section along the middle line of the gun carriage.

Referring to the drawing, 10 indicates the 25 gun mounted on the cradle 12 provided with trunnions 11. The gun carriage comprises an axle 13 supported by wheels 14 in the usual manner. Between the wheels is a trail comprising two trail members 15 30 mounted on the axle, said trail members being curved inwardly and connected at their forward ends at 16. Pivotaly mounted on the axle between the trail members is a platform 17 which extends forwardly and 35 is adjustably connected with the trail members by means of a rack 18 and worm gear 19. The platform may be raised or lowered by means of the gearing 20 and 21 and the hand wheels 22. One of the pairs of gears 40 21 is mounted on the transverse shaft 23 extending through both trail members and provided on opposite ends, outside of the trail members, with the hand wheels 22. The worm 19 is mounted in suitable bearings in the forward end of the trail. It 45 will be evident that the platform 17 may be raised or lowered by means of the hand wheels and gearing described.

Mounted on the platform 17 is a top carriage 24 in which the trunnions of the cradle have bearings. This top carriage is free to turn about a vertical axis over the axle 13 (not shown) but it is prevented from moving about a horizontal axis with re-

spect to the platform 17 by reason of the 55 lip 25 which engages a groove in the platform. The cradle carries a segment gear 26 by means of which it may be elevated or depressed to give the gun the proper elevation for any given target. The segment 60 gear is operated by means of a handle or hand wheel 27 through bevel gears 28, shaft 29, two sets of bevel gears 30 and worm 31. The wheel or handle 27 is mounted on an arm 32 of the top carriage 24 which arm 65 carries the level 33, scale 34 and an index 35, the latter being adjustable relatively to the scale 34 by means of a screw 36. The index 35 carries on its opposite side a pointer 37 adapted to coöperate with a range scale 70 38 which is fast on the cradle of the gun and concentric with the trunnions 11.

On the side of the gun opposite the arm 32 the top carriage 24 is provided with an arm 39 provided with two sights 40 and 41, 75 the former being an eye piece and the latter carrying cross hairs.

In one mode of operation of my improvements the top carriage is adjusted by means of the hand wheel 22, rack 18 and intermediate connections until the sighting devices 40, 41 show the cross hairs on the target, the gun having been properly traversed in azimuth by devices not shown in the present drawing, as the present invention 80 relates solely to elevating mechanism. The index point 35 is then brought to normal on the scale 34 by the thumb screw 36, after which the cradle is moved on its trunnions by means of the hand wheel 27 and connections until the range scale 38 shows the gun to have reached the proper elevation for the range of the target. If the range 85 on firing is found incorrect the gun can be readjusted by means of the hand wheel 27 without disturbing the position of the top carriage, the adjustment of which by means of the hand wheel 22 and connections may be considered permanent for any given 90 series of firings.

In another mode of operation the top carriage is leveled by means of the hand wheel 22 and the level 33 which is carried on the arm 32. The index 35 is then set with relation to the scale 34 to correspond to the 105 angle of the elevation of the target above or below the gun and the gun is then elevated until the pointer 37 indicates on the

scale 38 the elevation due to the distance of the target from the gun.

Having thus described the invention what I claim and desire to secure by Letters Patent is:

1. The combination with a gun carriage comprising an axle and suitable wheels, a support for a top carriage suitably mounted on the axle, means for adjusting said support about the axle, a top carriage on said support, a gun having bearings in the top carriage and independent means for adjusting the gun angularly about said bearings, the top carriage and gun each having a scale, and an index device carried by one of said parts and coöperating with both scales, for the purpose set forth.
2. The combination with a gun carriage comprising an axle and suitable wheels, a support for a top carriage suitably mounted on the axle, means for adjusting said sup-

port about the axle, a top carriage on said support, a gun having bearings in the top carriage and independent means for adjusting the gun angularly about said bearings, the top carriage having a scale and adjustable index and the gun having a scale co-operating with said index, for the purpose set forth. 25

3. The combination with a gun carriage comprising an axle and suitable wheels, of a top carriage adjustable angularly about the axle, sighting devices and an elevating arm carried by said top carriage, an adjustable index carried by said carriage, a gun mounted in trunnions on the top carriage, a range scale carried by the gun and means for adjusting the gun about its trunnion axis to bring any desired point on the range scale into coincidence with the index. 35 40

In testimony whereof I affix my signature.
JOHN LUND.
